UNITED STATES PATENT OFFICE.

BERTRAND E. BEYER, OF HOBOKEN, NEW JERSEY.

SAFETY ATTACHMENT AND LOCKING DEVICE FOR POWER-PRESSES.

1,258,525.

Specification of Letters Patent.

Patented Mar. 5, 1918.

Application filed August 13, 1917. Serial No. 185,958.

To all whom it may concern:

Be it known that I, BERTRAND E. BEYER, a citizen of the United States, residing at Hoboken, in the county of Hudson and State of New Jersey, have invented certain new and useful Improvements in Safety Attachments and Locking Devices for Power-Pres- 5 ses; and do hereby declare the following to be a full, clear, and exact description of the invention, such as will enable others skilled in the art to which it appertains to make and use the same, reference being had to the accompanying drawings, and to the letters and figures of reference 10 marked thereon, which form a part of this specification.

This invention relates to new and useful improvements in safety attachments and locking devices for power presses and so arranged that it would be impossible to operate the press until a guard is lowered to a protecting position.

The invention consists in the provision of a guard for power presses in which means is provided for permitting the guard to be swung out of place when it is desired to make adjustments, setting tools, etc., the apparatus being so arranged that the trip cannot be operated until the guard is in position and without obstruction in its path, the trip being locked until the guard reaches protecting position.

My invention comprises a simple and efficient apparatus of this nature having various details of construction, combinations and arrangements of parts which will be herein-after fully described, shown in the accompanying drawings and then specifically defined in the appended claims.

My invention is illustrated in the accompanying drawings which, with the letters of reference marked thereon, form a part of this application and in which:

Figure 1 is a side elevation showing the application of my invention to the frame of a power press.

Fig. 2 is an enlarged view, partially in section of the apparatus.

Fig. 3 is a sectional view on line 3—3 of Fig. 2.

Fig. 4 is a detailed view in elevation of the guard, and

Fig. 5 is a top plan view of the guard fastened to the frame of a press.

Reference now being had to the details of the drawings by letter:

A designates the frame of a power press having a pivotal trip lever B mounted upon a pivot C and D is a spring fastened at one end to the pin D' and its other end to one 60 end of the lever B. A bar, designated by letter E is pivoted to the trip lever B at E', and in turn is pivotally connected to the rod F, movable within the guide member H, which is fastened to the side of the frame by 65 passing bolts through apertures H' and holes in the frame. To the lower end of the rod F is fastened a yoke I, slotted as at I' and carrying a pivotal pin K upon which the lever L is pivoted. A tread lever N is 70 mounted upon a pin N' and has pivotal connection through the rod J with the lever L. A coiled spring O, is fastened at one end to the lever L and its other end to the guide member H, and tends to normally return the 75 tread lever and the lever L to their starting positions. A tubular shell Q is fitted in a recess in the member H at one end, and its other end is fastened to the hollow shell R, and Q' designates a latch which is adapted 80 to have longitudinal movement in an aperture H² formed through the wall of said member H and through the wall of the shell R. One end of the lever Q' is beveled and is adapted to engage a notch F' formed in 85 the bar F, and its other end projects into the bore of the shell R in the path of the longitudinally movable key T. A coiled spring T' is mounted upon the latch and bears intermediate the bottom of a recess in the 90 shell R and a pin T², passing through the latch Q', the purpose of which spring T' is to normally hold the beveled end of the latch in the notch F'. Said key T is guided in its longitudinal movements in the key way 95 R' and has a notch R² in the edge thereof, adapted to receive one end of the latch Q', when the guard is lowered to protecting position.

A guard carrying tubular member S, which is provided with perforations 100 S', has a longitudinal slot S² to receive the key T and a lug T³ upon said key is adapted to engage one or another of the perforations S', for the purpose of holding the key and tubular member S in different relative positions according as it may be desired to hold the guard S³ at different elevations. A stud X projects from the member S and carries an

anti-friction wheel S⁴ and is adapted to be engaged by the lever L, for the purpose of raising the guard S⁵.

In operation, by pressing on the tread lever, the lever L may be drawn down under tension of the spring O. As the guard is operated by the lever L when the latter is lowered, the guard will lower by gravity to protecting position. As the lever L swings down and comes in contact with the lower edge of the slot I', the yoke will be drawn down and with it the rod F. As the rod F lowers, the beveled edge of the notch therein will cause the latch Q' to be released therefrom and as the guard will have reached its lowest limit before the latch is withdrawn from the notch F', the opposite end of the latch will engage the notch R² and lock the guard at its lowest position. As the rod F is moved downward, the trip actuating the power press will be operated after the guard is held in its lowest position. When the operator releases pressure from the trip lever, the spring D will cause the rod F to be raised, so that the notch F' will come into alignment with the latch, thus permitting the guard member to be raised through the medium of the spring O.

It will be understood that the trip rod is always pulled in place by the spring D. Should the hand of the operator obstruct the path of the guard, which may be lowered at the will of the operator, as soon as the guard touches the obstruction or hand, further descent of the guard will be checked, as it moves downward by its own weight, while the lever L will move only until it has reached the limit, governed by the length of the slot I' in the yoke I. By reason of the longitudinal movement of the latch Q' in one direction being limited by the key T until the guard is lowered sufficiently to permit registration of the notch R² with the latch, a positive lock is afforded to the trip mechanism by reason of the latch being held in the notch of the rod F, thus preventing downward movement of the rod F and actuation of the trip lever B.

The tubular shell S and T may be raised to permit the offset of the key or portion above the notch R² to come out of the key-way within the shell R and the guard at the lower end may then be swung out of position. The key will ride on the top of the shell R and will not permit the guard to be lowered and the press to be tripped until the adjusting key means is again properly set and entered in the key-way.

What I claim to be new is:

60 1. A safety attachment and locking device for power presses, comprising, in combination with the frame of a power press, a pivotal spring pressed trip lever, a trip operating rod, a yoke fastened to said rod, a longitudinally movable guard and support

therefor, a spring pressed guard raising lever pivoted to said yoke, a tread lever connected to the guard raising lever, and a spring pressed latch normally locking the trip rod when the guard is in an elevated 70 position.

2. A safety attachment and locking device for power presses, comprising, in combination with the frame of a power press, a pivotal spring pressed trip lever, a longitudinally movable trip operating rod with a yoke at one end and a bar pivotally connecting said rod and lever, a bearing for said rod, a lever pivoted to the yoke, a spring actuated latch adapted to normally 75 lock said rod, a shell in which one end of the latch is mounted, a guard provided with a tubular portion having a longitudinal movement in said shell, a key adjustably connected to said tubular portion and provided with a notch to be engaged by one end of the latch, said guard being elevated by the lever which is pivoted to the yoke, as set forth.

3. A safety attachment and locking device 90 for power presses comprising, in combination with the frame of a power press, a pivotal spring pressed trip lever, a casting for attachment to the frame, a notched rod movable through said casting and having a slotted yoke at one end, a spring pressed lever pivoted to the yoke, a tread lever, a rod pivotally connecting the latter and lever which is pivoted to the yoke, a tube projecting from said casting, a shell secured to 95 said tube, the walls of the shell and casting being apertured, a spring pressed latch mounted to have a longitudinal movement in said apertures and designed to engage the notch in said rod, a guard having a tubular 100 shaft which is apertured, a notched key adjustably connected to said tubular shaft and movable in a key-way in said shell, said key adapted to be engaged frictionally by one end of the latch, a stud projecting from 105 the tubular shaft, and an anti-friction wheel journaled upon the stud and engaged by the lever which is pivoted to the yoke.

4. A safety attachment and locking device 110 for power presses comprising, in combination with the frame of a power press with a spring pressed pivotal trip lever, a casting for attachment to the frame, a notched rod movable through said casting and having a slotted yoke at one end, a spring pressed lever pivoted to the yoke, a tread lever, a rod pivotally connecting the latter and lever which is pivoted to the yoke, a tube projecting from said casting, a shell secured to said 115 tube, the walls of the shell and casting being apertured, a spring pressed latch engaging said apertures, one end of the latch adapted to enter the notch in said rod, a guard having a perforated tubular shaft slide- 120 able in said shell, a notched key movable in 125 said shell, and a tread lever connected to the guard raising lever.

a key-way in said shaft, said key having a lug adapted to engage the perforations of said tubular shaft, a stud carried by the tubular shaft, and an anti-friction wheel 5 journaled upon the stud and against which said lever pivoted to the yoke is adapted to contact.

5. A safety attachment and locking device for power presses comprising, in combination with the frame of a power press, a pivotal spring actuated trip lever, a casting secured to the frame, a notched rod movable in said casting and having a yoke at one end with an elongated slot therein, connections 10 between said rod and trip lever, a spring pressed lever pivoted to said yoke and having a swinging movement in said slot, tread lever and connections between the same and the lever which is pivoted to the yoke, a

tube fastened to said casting, a shell secured 20 to one end of the tube, said tube and shell having registering apertures, a spring pressed latch movable in said apertures, a key movable in a suitable key-way in said shell and provided with a projecting lug and 25 a notch, a guard member having a tubular shaft, perforated and adapted to receive said key, a stud projecting from said shaft, an anti-friction wheel upon said stud and adapted to be engaged by the lever which 30 is pivoted to said yoke.

In testimony whereof I hereunto affix my signature in presence of two witnesses.

BERTRAND E. BEYER.
